Primary Examiner—Caron Veynar*Assistant Examiner*—Ricky Pham(74) *Attorney, Agent, or Firm*—Pabst Patent Group LLP(57) **CLAIM**

The ornamental design for a round vented container, as shown and described.

DESCRIPTION

FIG. 1 is a side elevational view of the container with lid, with the other side elevational views being mirror images thereof;

FIG. 2 is a top plan view of the container with lid;

FIG. 3 is a bottom plan view of the container with lid;

FIG. 4 is a perspective view of the container with lid;

FIG. 5 is a side elevational view of the container, with the other side elevational view being a mirror image thereof; shown without the lid for ease of illustration;

FIG. 6 is a perspective view of the container;

FIG. 7 is a side elevational view of the lid, with the other side elevational view being a mirror image thereof; shown without the container for ease of illustration;

FIG. 8 is a top plan view of the lid; and,

FIG. 9 is a bottom plan view of the lid.
